(57) **CLAIM**

The ornamental design for the round container with lid, as shown and described.

DESCRIPTION

FIG. 1 is a perspective view of the round container with lid with the door in the closed position;

FIG. 2 is a perspective view of the round container with lid as shown in FIG. 1, but with the door in the open position; FIG. 3 is a top view of the round container with lid as shown in FIG. 1;

FIG. 4 is a top view of the round container with lid as shown in FIG. 2;

FIG. 5 is a rear view of the round container with lid as shown in FIG. 1;

FIG. 6 is a front view of the round container with lid as shown in FIG. 2;

FIG. 7 is a side view of the round container with lid as shown in FIG. 1;

FIG. 8 is a bottom view of the round container with lid of FIG. 1;

FIG. 9 is a side view of the round container with lid as shown in FIG. 2, taken from the right; and,

FIG. 10 is a cross-sectional view of the round container with lid as shown in FIG. 4.
